GEORGE D. FITZHUGH, OF LOS ANGELES, CALIFORNIA, ASSIGNOR TO CLAUDE NEON ELECTRICAL PRODUCTS CORPORATION, LTD., OF WILMINGTON, DELAWARE, A CORPORATION OF DELAWARE

ILLUMINATED SIGN CONSTRUCTION

Application filed May 18, 1931. Serial No. 538,022.

My invention relates to illuminated sign constructions, and has particular reference to a background for signs employing tubular lamps as the source of illumination. In the art of sign construction, employing tubular lamps for outlining the sign indicia, the tubular lamps have heretofore been mounted upon a relatively dull or non-reflective background, so that the sign presents the appearance of sharply defined sign indicia as the luminous portion, while the remainder of the sign is illuminated only by such small diffusion of light which occurs from the employment of the tubular light sources.

It is an object of my invention to provide a sign having tubular lamps outlining indicia thereon with a background of reflective material to produce the appearance of a multiplicity of sources of illumination.

Another object of my invention is to provide a background for luminous tube signs in which a reflective background is employed, the background being formed of a finely corrugated material having a varied contour relative to the plane of the luminous tubes.

Other objects of my invention will be apparent from a study of the following specification, read in connection with the accompanying drawings, wherein

Figure 1 is a front elevational view of a sign and background constructed in accordance with my invention, and

Figure 2 is a sectional view taken along the line II, II of Figure 1.

Referring to the drawings, I have illustrated a sign construction comprising a base board or back board 1, upon which the sign background and indicia ought to be mounted. The sign indicia is illustrated as being formed from a plurality of luminous tubes 2, 3, 4 and 5 which may be of any suitable character, for example, the Neon gaseous discharge tube type.

Each of the tubes 2, 3, 4 and 5 may be bent in any desired configuration to form the desired indicia or decoration desired to be employed, each of these tubes being supported upon the back plate 1, as by means of forwardly projecting tube supports 6 secured to the tube and to the back plate in any suitable

manner well-known to those skilled in the art of tubular sign construction.

I have illustrated a reflective background member 7 interposed between the plane of the tubes 2, 3, 4 and 5 and the plane of the backing plate or board 1, this reflective member being preferably formed of highly polished metal or metal plated with reflective material, such as chromium. By referring particularly to Figure 2, it will be observed that the reflective background 7 does not lie flat upon the backing board or plate 1, but is provided with a varied contour. In the embodiment of the invention shown the background plate 7 is illustrated as being formed of a plurality of flat sections 8 spaced from each other, between each adjacent pair of which the background member is bent forwardly into a substantially V-shaped contour, indicated at 9, 10 and 11.

A pleasing result may be obtained by locating the point of the V directly behind the center point of any selected symmetrical portion of the sign motif. For example, the tube 3 is illustrated as outlining a "shield" shape, and in this instance the point of the V 9 is located immediately behind the center line of the "shield" shape.

Thus, the reflection 12 of the "shield" shaped tube 3 presents the appearance of a second shield shape considerably distorted from the shape of the tube 3.

Further enhancement of the appearance of the sign may be obtained by corrugated portions of the reflective background 7, as is indicated at 13, the corrugations constituting parallel lines throughout the entire area of the reflective background member 7 or the corrugations may be varied throughout the background as by providing some of the corrugations extending vertically, while other corrugations, indicated by the reference character 14, may be formed with their lines running horizontally. If desired, the flat spaces 8 between the V contours may be left uncorrugated for further enhancing the appearance of the sign.

The employment of the construction hereinbefore described produces a sign in which the luminous tubes present the sign indicia in

brightly illuminated lines, while the distorted reflection of these lines produces an appearance of a multiplicity of other luminous sources, but of considerably less luminosity than the actual tubes from which the light comes.

While I have shown and described the preferred embodiment of my invention, I do not desire to be limited to any of the details shown or described herein, except as defined in the appended claims.

I claim:

1. In a sign construction, a support, a luminous tube bent into a preselected design, means mounting said luminous tube in spaced relation to said support, a reflective background interposed between said tube and said support having a cross sectional contour including a plurality of V-shaped portions pointed toward said tube.

2. In a sign construction, a luminous tube bent into a pre-selected design, a supporting means mounting said tube, a reflective background interposed between said tube and said support having a cross-sectional contour including a plurality of V-shaped portions pointed toward said tube, each of said V-shaped portions being corrugated.

3. In a sign construction, a luminous tube bent into a symmetrical shape to form sign indicia, a supporting means mounting said tube and a reflective background member interposed between said support and said tube, said background member having a cross-sectional contour including a plurality of spaced V-shaped portions, the points of the V's being aligned with the center line of the shape produced by said tube.

Signed at Los Angeles, Calif., this 8th day of May, 1931.

GEORGE D. FITZHUGH.
